(57) **CLAIM**

The ornamental design for a portion of a chair back, as shown and described.

DESCRIPTION

FIG. 1 is an isometric view of a portion of a chair back showing my new design.

FIG. 2 is a front view thereof.

FIG. 3 is a top view thereof.

FIG. 4 is a bottom view thereof.

FIG. 5 is a right side view thereof; and,

FIG. 6 is a left side view thereof.

The broken lines shown in FIGS. 1-6 are included for the purpose of illustrating environmental elements only and form no part of the claimed design. The dotted line shown in FIGS. 1-3 and 5-6 represents an unclaimed border between claimed and unclaimed subject matter forms no part of the claimed design. The rear view is omitted and forms no part of the claimed design.
